[57] **CLAIM**

The ornamental design for jaw protector for removably covering the jaw members of a gripping tool, as shown and described.

DESCRIPTION

FIG. 1 is a side perspective view of a jaw protector for removably covering the jaw members of a gripping tool, showing my new design;

FIG. 2 is a side elevational view; and,

FIG. 3 is an end perspective view.

The front view of the jaw protector forms no part of the claimed design.
